UNITED STATES PATENT OFFICE.

LUBIN PARADIS, OF CAMBRIDGE, AND NARCISSE DESROSIERS, OF BOSTON,
MASSACHUSETTS.

HANSOM-CAB.

SPECIFICATION forming part of Letters Patent No. 634,651, dated October 10, 1899.

Application filed November 17, 1898. Serial No. 696,661. (No model.)

To all whom it may concern:

Be it known that we, LUBIN PARADIS, a citizen of the United States, residing at Cambridge, in the county of Middlesex, and NARCISSE DESROSIERS, a subject of the Queen of Great Britain, residing at Boston, in the county of Suffolk, in the State of Massachusetts, have invented certain new and useful Improvements in Hansom-Cabs, of which the following is a specification.

Our invention relates to that class of two-wheeled vehicles known as "hansom-cabs;" and the invention consists in the means of operating the window and the folding doors from the driver's seat, as hereinafter set forth, and pointed out in the claims.

Referring to the accompanying drawings, Figure 1 represents a side view, partially in section, of a hansom-cab embodying our invention. Fig. 2 is a plan or top view of the same, a portion of the roof being broken away in order to show the window and door operating mechanism. Fig. 3 is a side view of the tubes or cylinders for carrying the brackets of the upper end of the window-sash. Fig. 4 is a plan or top view of same. Fig. 5 is an end view of one of the angle-pieces carrying rollers for guiding the window-sash. Fig. 6 is a side view of same. Fig. 7 is an end view of one of the curved arms secured to the window-sash. Fig. 8 is a side view of same. Fig. 9 is a plan or top view of the upper door-hinge. Fig. 10 is a side view of same, and Fig. 11 is a side view of the top leaf of the hinge detached. Fig. 12 is a side view of the spindle and sprocket-wheel for said hinge. Fig. 13 is a plan or top view of the cap or cover for the spindle and sprocket-wheel. Fig. 14 is a side view, and Fig. 15 is a longitudinal section, of same. Fig. 16 is a side view of a toothed wheel on the end of the rod for imparting motion to the doors. Fig. 17 is a plan or top view of the ring or sprocket-wheel having internal teeth. Fig. 18 is a vertical section through the same.

A represents the body of the cab or carriage, carried by springs B, secured to the axle C in the usual manner.

D represents the doors, and E the window. Now supposing the same to be in the closed position, as shown in Fig. 1, and it is desired

to raise the window and open the doors, the driver first operates the lever F and then the lever G on the outside of the roof of the cab, said levers operating mechanism as follows: 55 On the shaft carrying the handle F is secured a sprocket-wheel f, and to the frame above the window is secured another but smaller sprocket-wheel g, around which wheel passes a sprocket-chain H, and to the upper end of 60 the window-sash E are secured brackets e, connected by arms e' to tubes or cylinders d, (see Figs. 3 and 4,) free to slide upon rods I, that extend longitudinally from end to end of the cab a short distance from the center, 65 said tubes or cylinders d being connected together by a cross-bar d', having at or near its center a rearward-projecting piece d'', to which the chain H is attached. This chain passes over the sprocket-wheel g, secured to the top of the window-frame, and over the sprocket-wheel f, secured on the short shaft, to which the operating-lever F is secured. Thus as soon as the lever F is turned in the direction for raising the sash 70 the tubes or cylinders d are drawn backward, and with them the upper end of the sash, causing it to tilt, and as it is drawn farther back it is guided in the proper manner by means of angle-pieces J, secured to each 75 side of the window-frame, (see Figs. 5 and 6,) each angle-piece having an inwardly-projecting arm j, upon which are mounted two rollers i i', and a curved arm K is secured on each side of the window-sash, (see Figs. 7 80 and 8,) so that when the sash is being raised 85 the upper end e of said arms come into contact with the lower roller i of the arm j, and as the movement is continued to raise the said sash it is tilted until sufficiently drawn 90 up, when said arms come into contact with the rollers i', and when drawn sufficiently far back the recesses k in the arms K rest upon the upper rollers i', thereby supporting the front end of the window-sash, the rear 95 end being held by the brackets e, as before described. Thus the window is held under the roof. When it is desired to lower the same, all that has to be done is to turn the hand-lever F in the opposite direction. The upper 100 hinge L of each door is constructed as follows, (see Figs. 9, 10, and 11:) The top leaf l

is formed with a downwardly-projecting stem l' , through which is formed a square tapering hole l^2 , and the lower leaf l^3 is formed with a round hole to receive the stem l' . The upper leaf is thus supported by the lower one. Through the square tapering hole l^2 is passed a correspondingly-shaped spindle (see Fig. 12) having at its lower end a screw-thread to receive a nut m and having at its upper end a small sprocket-wheel n . Over this hinge and sprocket-wheel is secured a cap or cover M of the form shown in Figs. 13, 14, and 15, so that rain or water cannot pass to the inside of the cab.

15 N N are upright rods, one secured on each side of the cab. On the upper end of each of these rods is secured a sprocket-wheel P , and its lower end is formed with a cog-gear N' , having rounded teeth (see Fig. 16) that fit into a ring P , having correspondingly-formed internal teeth, (see Figs. 17 and 18,) so that said ring P and the rod N are free to be placed at any desired angle in relation to each other, the ring P being also formed with 20 a sprocket-wheel on its periphery and also with a short stem p , by which it is supported in a bearing secured to the side of the cab. A sprocket-chain Q passes around the ring and the sprocket-wheel m of the hinge L . It is 25 obvious that this construction might be reversed—that is to say, the ring might be on the end of the upright rod and the wheel having curved teeth working therein might be formed on a short shaft that also carries a sprocket-wheel to communicate motion to the 30 hinge L .

R is a double sprocket-wheel secured on the lower end of a short shaft that carries the hand-lever G , and S S' are sprocket-chains that pass around the wheel R and the wheels P^2 on the upper ends of the rods N , one of which chains S' has to be crossed in order that the doors may be thrown open.

40 It will be seen that by the above construction the window is raised and lowered by simply turning the arm F , and the doors are opened and closed by the movement of the lever G .

What we claim is—

50 1. A cab, a window for the front thereof, brackets secured to its upper edge, arms connecting said brackets to tubes or cylinders connected together by a cross-bar, rods on each side near the center of the roof for said tubes or cylinders to slide upon and means for imparting motion to the cross-bar to operate said tubes or cylinders as set forth.

2. A cab having near the central portion of its roof, two longitudinal rods, tubes or 55 cylinders adapted to slide upon said rods and connected together by a cross-bar, a window, brackets connected to the upper edge of the window and to said tubes or cylinders, and means for operating the cross-bar to impart motion to said tubes or cylinders and the window-sash as set forth.

3. A cab, a window for the front thereof

and curved arms secured to the sides of the window-sash, in combination with angle-pieces secured to the sides of the window-frame each having two rollers mounted thereon whereby when the window is being raised the curved arms will come into contact with the lower roller and the lower end of the sash will be thrown outward and when the sash is 70 fully raised it will be supported by the curved arms resting upon the upper rollers on the angle-pieces as set forth.

4. A cab, folding doors for the same, a hinge consisting of two leaves the upper one 80 having a downwardly-projecting stem and the lower leaf a hole to receive it, a square tapering spindle passing through a correspondingly-shaped hole in the stem and secured at its lower end by a nut, a sprocket-wheel upon 85 the upper end of said spindle and means for operating said sprocket-wheel to operate the doors as set forth.

5. A cab folding doors for the same, a hinge, a sprocket-wheel on its spindle, a ring 90 supported by a bracket and having a sprocket-wheel on its periphery and concave cog-teeth on its inner face a sprocket-chain for communicating motion from one sprocket-wheel to the other, an upright rod, a curved cog-wheel on its lower end adapted to work in 95 said ring, a sprocket-wheel on the upper end of said rod and means for operating same as set forth.

6. A cab, folding doors for same, a hinge 100 having a square tapering spindle, a sprocket-wheel on its upper end, a ring having sprocket-teeth on its periphery and cog-teeth on its inner face, said ring being situated inside the cab, a sprocket-chain for imparting motion 105 from the ring to the sprocket-wheel on said spindle, an upright shaft, a curved cog-wheel secured to same and working in said ring whereby motion is transmitted from the upright rod to the hinge as set forth.

7. A cab folding doors for same, a hinge 110 having a square tapering spindle, a sprocket-wheel on same, means for operating said sprocket-wheel in combination with a cap or cover over said hinge and sprocket-wheel as 115 set forth.

8. A cab, a window for the front thereof, brackets secured to its upper edge, tubes or cylinders connected to said brackets, said tubes or cylinders being connected together 120 by a cross-bar, a sprocket-wheel secured to the window-frame, a short rod passing through the roof a lever on the upper end thereof, a sprocket-wheel on its lower end and an endless sprocket-chain passing over said sprocket-wheels and attached to the cross-bar connecting the tubes or cylinders as set forth.

9. A cab folding doors for same, a hinge 125 having a square tapering spindle, a sprocket-wheel on said spindle, a ring, supported by a bracket and having a sprocket-wheel on its periphery and curved cog-teeth on its inner face, a sprocket-chain for communicating motion from the sprocket-wheel on the ring

to the sprocket-wheel on the tapering spindle an upright rod on each side having curved cog-teeth on its lower end adapted to work in said ring and a sprocket-wheel at its upper end, a short shaft passing through the roof, a lever on its upper end and a double sprocket-wheel on its lower end, sprocket-chains for communicating motion from said double sprocket-wheel to the sprocket-wheels

on the upright shafts one of said chains being crossed as set forth.

In testimony whereof we have affixed our signatures in presence of two witnesses.
